FUSE-ADJUSTING KEY.

1,005,762. Specification of Letters Patent. Patented Oct. 10, 1911.

Application filed October 7, 1907. Serial No. 396,345.

To all whom it may concern:

Be it known that I, FRIEDRICH ZIEGENFUSS, a subject of the Emperor of Germany, and a resident of Essen-on-the-Ruhr, Germany, have invented certain new and useful Improvements in Fuse-Adjusting Keys, of which the following is a specification.

The present invention relates to the type of fuse adjusting keys which is provided with a securing bolt which is releasable by hand and which in its securing position prevents the adjusting key being lifted off the fuse. In the fuse adjusting key according to the present invention the bolt is so arranged on the key and enters into engagement with the fuse in such a manner that when the key is rotated to adjust the fuse the bolt is capable of partaking of the rotation of the key.

By "a bolt which in its securing position prevents the adjusting key being lifted off the fuse" is meant a bolt which while engaging the fuse, prevents relative movement of the fuse and key in the direction of the longitudinal axis of the fuse and which consequently must be released by hand and is not automatically released when the key is lifted off the fuse, as is the case with the adjusting noses of the known fuse adjusting devices.

In the accompanying drawings, Figure 1 shows a section through one embodiment of the invention, by way of example; Fig. 2 shows a plan view of Fig. 1, partly in section; Fig. 3 shows a side view, partly in section, of a burning time fuse; and Fig. 4 is a plan view of Fig. 3, partly in section.

The annular body A of the adjusting key is provided with an arm A' and contains a ring B which can rotate in the body A but is held from axial displacement therein. The ring B can be adjusted relatively to the body A through the medium of a worm C which is journaled in the body A and which meshes with the toothed periphery b' of the ring. On the upper surface of the ring B is secured a scale carrier b², which has its scale b³ visible through a window a² (Fig. 2) which is provided in the body A and has a mark a³ at its edge. In the ring B is swingingly arranged a spring-pressed latch b⁴ for which a notch d' is provided in the fuse base D. The body A is provided with a stud a⁴ which is diametrically opposite to the arm A' and which fits in a notch e'

provided in the rotatable composition ring E of the fuse. The latch b⁴ and the corresponding notch d' and also the stud a⁴ and the corresponding notch e' are formed in such a manner that the latch b⁴ and the stud a⁴ can pass out of engagement with the corresponding notch d' and e' when the adjusting key is withdrawn from the fuse.

The arrangements so far described are old.

In the body A a bolt F is mounted diametrically opposite to the stud a⁴. The bolt F is held from rotation and is arranged in such a manner that it can move in a direction which is radial to the axis of the body A. A spring f' tends to hold the bolt in the position in which its inner end f' projects beyond the inner periphery of the body A. For the end f' of the bolt F a notch e² is provided in the rotatable composition ring E of the fuse. The notch e² is located the same angular distance from the notch e' as the bolt F is from the stud a⁴, and when the stud a⁴ engages in the notch e' the bolt F can, therefore, at the same time engage in the notch e². The notch e² and the end f' of the bolt F are formed in such a manner that the bolt F cannot be brought out of engagement with the notch e² by a force that tends to lift the key from the fuse.

The outer end of the bolt F, on which is screwed a head f² having two trunnions f³, projects into a recess a⁶ in the arm A', the recess being closed by the two cover-plates a⁵. The head f² is straddled by the bifurcated arm G' of a bell crank lever G' G² arranged in the recess a⁶ of the arm A' and the arrangement is selected in such a manner that the trunnions f³ project into the path of the arm G' and that the bolt F, by a turning of the bell crank lever G' G² in the direction of the arrow x (Fig. 1) can be moved so far outwardly that its end f' does not any longer project beyond the inner periphery of the body A. The arm G² of the bell crank lever G' G² has its outer end projecting into the path of a bolt H which is axially movable in a handle a⁷ which is rigidly secured to the arm A'. The bolt H is provided with a collar h' over which is fitted a screw-cap a⁸ which is screwed on the handle a⁷. On the cap a⁸ is slidably arranged a bell-shaped press-piece h² which is rigidly secured to that end of the bolt H

which projects outside of the cap a^8 . A spiral spring J tends to hold the bolt H and the press-piece h^2 in the position shown in the drawing.

- 5 After the adjusting key has been adjusted by means of the worm C , the key is inserted on the fuse in such a position that the stud a^4 comes into engagement with the notch e^2 . While this takes place the bolt F is first
 10 forced back in its bearing and is subsequently brought into engagement with the notch e^2 by the spring f^4 . The adjusting key is then secured against being lifted off the fuse and it is immaterial whether the
 15 force acting to lift off the adjusting key tends to effect a displacement of the key in the direction of the axis of the projectile or whether the force tends to place the key on edge relatively to the fuse. After the key
 20 has been placed on the fuse the key is, by means of the handle $a^7 h^2$, turned in the direction of the arrow y (Fig. 2) until the latch b^4 , which while the key was being placed on the fuse was forced entirely back in the body
 25 A , enters the notch d' in the fuse base D . The desired adjustment has then been imparted to the fuse. The bell shaped press piece h^2 is then pressed downwardly until the collar h' of the bolt H abuts against the
 30 handle a^7 . This causes the bolt F to pass out of engagement with the notch e^2 and the adjusting key can then be lifted off the fuse.

The improved securing means for preventing the key being lifted off the fuse is simpler than the known devices of the same type. Furthermore it is directly applicable to the type of adjusting keys which is shown in the drawing and which is of very simple and compact construction.

- 35 40 Having thus described the invention, what is claimed as new and desired to secure by Letters Patent is:—

1. A fuse adjusting key having setting members provided with means for coupling them to the fixed and movable parts respectively of the fuse, and a manually re-

50 leasable bolt constructed to engage and cooperate with the fuse and hold the key against displacement in the direction of the axis of the fuse.

55 2. A fuse adjusting key having setting members provided with means for coupling them to the fixed and movable parts respectively of the fuse, a bolt movably mounted on one of said members in position to engage a part of the fuse in the direction to resist removal of the key from the fuse, and manually actuated means adapted to move said bolt, relatively to the key, out of engagement with the fuse.

60 3. A fuse adjusting key comprising an operating handle and two relatively rotatable adjusting members having means for coupling them to the respective members of the fuse, a bolt mounted on one of said adjusting members in position to engage a part of the fuse in the direction to resist removal of the key from the fuse, and means for manually actuating the bolt to effect the release of the key from the fuse, said actuating means being mounted on said handle whereby the handle and the actuating means may be manipulated by one hand of the operator.

65 70 4. In a fuse adjusting key adapted to be applied to the fuse by an axial movement relatively to the fuse and comprising two relatively rotatable adjusting members having means for coupling them to the respective members of the fuse, a bolt mounted on one of said adjusting members and adapted to be coupled to the adjustable fuse element and resist removal of the key from the fuse, and manually operable means adapted to move said bolt out of engagement with the adjustable fuse element.

75 80 85 The foregoing specification signed at Dusseldorf, Germany, this 31st day of July, 1907.

FRIEDRICH ZIEGENFUSS.
In presence of—

ALFRED POHLMÉYER,
M. ENGELS.
